UNITED STATES PATENT OFFICE

EDWARD W. N. BOOSEY, OF DETROIT, MICHIGAN

GUTTER OR ROOF DRAIN

Application filed August 22, 1929. Serial No. 387,574.

This invention relates to gutter or roof drains, the object being to provide a very simple and inexpensive construction for connection with a drain line such as the down-spout or conductor pipe of a gutter or other drainage conduit for waste fluids.

The purpose of the invention is not only to materially reduce the weight of such structures but to reduce the cost of installation and 10 to secure a more efficient and serviceable structure for the purpose in which the screen member is attached directly to the conductor or waste conduit either by being threaded directly thereonto or to a member attached to 15 the conduit or conductor.

Previous structures of this nature include a considerable number of parts such as a bowl and fastening device of various forms to secure the parts together requiring considerable 20 machining and labor in assembly which are materially reduced in my improved construction in which there are only two parts in addition to the conductor or waste conduit and the flashing or gutter bottom connected 25 therewith.

These and other objects and the several novel features are hereinafter more fully described and are shown in preferred form in the accompanying drawing in which—

30 Fig. 1 is a cross section of a gutter showing my improved sump or drain partly in section connected therewith.

Fig. 2 is a similar view of an alternative form of construction.

35 My improved drain or sump is shown in Fig. 1 in conjunction with a conductor or down spout for a gutter 1. The sump consists of a cylindrical screen member 2 having vertical slots 3 in the side wall and radial slots 4 in dome shaped upper end thereof and at the bottom is provided with an internally threaded ring portion 5 which is somewhat less in diameter than the internal diameter 40 of a hub 6 into which the ring 5 of the screen member may be readily introduced. This hub not only has the vertical portion indicated at 7 but also has an annular flange 8 extending outwardly from the vertical portion 7 forming a V shaped recess 9 into which the bottom wall 10 of the gutter may be posi-

tioned; the bottom wall of the gutter being apertured to receive the hub member. This hub member is preferably of brass and the gutter, especially in commercial buildings, is usually formed of copper and thus with this character of material a solder 11 may be poured into the V recess 9 to cover the in-turned end of gutter bottom or roof flashing as the case may be whereby the copper gutter bottom is soldered to the brass hub. This hub also has a threaded aperture formed therein and a short extending portion 12 adapting the same to be threaded onto the upper end of the conductor 13 usually an iron pipe. These threads in the member 12 are 55 pipe threads but are sufficiently large to thread a considerable distance onto the threaded end of the pipe section whereby the upper end 14 of the pipe extends upwardly 60 into the hub nearly flush with the upper end 65 of the vertical walls 7 of the hub. 70

This provides a projecting pipe end onto which the internally threaded ring 5 at the bottom of the screen member may be threaded and anything passing the screen flows directly into the conductor or waste conduit 13 instead of into a bowl as has usually been the practice. If for any reason it is necessary to examine the interior of the conductor or waste pipe 13, or in order to clear the same of any obstruction, the screen member may be unthreaded without disturbing the assembled 75 relation of the flashing and hub and conductor in providing access to the interior of the pipe 13. In previous structures it was necessary to disassemble a considerable number of parts to clean the bowl for instance but by my arrangement this labor is performed with the least expenditure of effort possible, it 80 being only necessary to unscrew the screen member from the pipe, and when the examination has been completed it is simply screwed back to place and the relationship of the parts otherwise is undisturbed. Furthermore, due to the absence of a bowl or 85 catch basin as has been usual heretofore in which dirt accumulates, there is ordinarily less necessity for examination of the sump 90 made according to my improved construction 95 as such material is discharged from the gut- 100

ter or roof practically as rapidly as it accumulates passing to the waste pipe which is of ample capacity to carry fluid containing considerable solid matter. By thus disposing of the same practically as rapidly as accumulated it does not pile up and finally prevents operation of the sump as is the case with ordinarily used structures which definitely provide for an accumulation of waste solid material therein.

Thus at all times the sump disposes of waste solid matter with fluid passing into the sump and the screen member prevents solid material of a size sufficient to clog the down spout from passing thereto. For this reason the screen member 2 is made of considerable height vertically, the slots running longitudinally thereof as shown so that for a long period of time waste material of too great a size to pass the screen may accumulate in the gutter or on the roof about the screen member without flow through the screen member being stopped. It is often-times convenient to run the usual iron pipe 25 formed with a hub at one end to the roof or gutter as the case may be and I have indicated such an arrangement in Fig. 2 in which the iron pipe is indicated at 20 having the hub 21 into which the roof flashing or gutter bottom 22 may be inturned. To connect my screen member 2 therewith, which is the same screen member as shown in Fig. 1, I use a short length of pipe 23 preferably with a flanged end 24 of the same internal diameter as the pipe for seating on the shoulder of the hub. This may be caulked in place as by caulking 25 and the upper end thereof is threaded to receive the threaded ring 5 of the screen member in the same manner as the upper threaded end of the pipe 13 of Fig. 1 is used. The roofing or flashing 22, or in the case of use of the device of Fig. 2 with a gutter the gutter bottom, will have its edge about the opening therein for the waste conduit inturned into a hub 21 of the pipe 20 and in caulking the pipe 23 in place the inturned edge of the flashing or roofing or gutter bottom is secured in place within the hub.

In this latter construction the screen member may be removed without disturbance of the remaining parts as is the case with the construction shown in Fig. 1 and all the objects of the invention are attained by either form of the device illustrated.

From the foregoing description it is evident that the device is of extreme simplicity and inexpensiveness of construction, and that the device is of even greater efficiency than the usual devices for this purpose, and a repair or cleaning of a clogged outlet is very readily accomplished by either of the structures described.

Having thus briefly described my invention, what I claim is—

1. In a gutter or roof drain in which a

screen member is associated with a conduit for the discharge of waste fluid material, a hub positioned on the waste conduit in a manner to provide a cylindrical recess about the end of the conduit, a tubular screen member having a lower open end secured in the recess and extending vertically above the conduit end, the edge of the roof or gutter bottom being secured to the hub in watertight relation, the said hub end being practically flush with the end of the waste conduit and the cylindrical recess being concentric therewith into which the screen member may be introduced.

2. In a gutter or roof drain in which a screen member is associated with a conduit for the discharge of waste fluid material, a hub member adapted for threaded relation with the end of the waste conduit and positioned with the end thereof practically flush with the end of the conduit and providing a cylindrical recess permitting introduction of the end of the screen member thereto, a tubular screen member having a lower open end threaded for engagement with the end of the conduit and lying in the recess and extending vertically above the conduit end, said hub member further having a flange to receive the edge of the flashing or gutter bottom, and means for securing the same therein in water-tight relation.

3. In a roof or gutter drain in which a waste conduit extends to practically flush with the roof flashing or gutter bottom, a brass hub member having a threaded end portion for engagement with the threaded upper end of the conduit, the end of the hub being positioned practically flush with the end of the conduit and plane of the flashing or gutter bottom, said hub being of a form to provide an annular recess about the conduit at the end, a tubular screen member having a lower open end threaded for engagement with the end of the conduit and lying in the recess and extending vertically above the conduit end, an integral flange extending outwardly from the hub providing an annular recess into which the gutter bottom or roof flashing may be inturned to below the hub end, and a solder in the recess covering the end of the flashing.

4. In a roof or gutter drain having a conduit for the discharge of waste fluid provided with a threaded end, a brass hub threadable on the conduit providing an annular recess between the end of the conduit and the inner face of the hub, the axis of which coincides with the conduit axis, a tubular screen member having a lower open end threaded for engagement with the end of the conduit and lying in the recess and extending vertically above the conduit end, an integral upwardly inclined flange terminating practically flush with the upper end of the hub into which the gutter bottom or roof flashing may be in-

turned, the arrangement providing that the upper end of the conduit and of the hub are practically flush with the roof flashing or gutter bottom, and a solder in the recess for securing the gutter bottom or flashing in place and covering the inturned end thereof.

5 In testimony whereof I sign this specification.

EDWARD W. N. BOOSEY.
